UNITED STATES PATENT OFFICE

WALDO J. GUILD, OF WORCESTER, MASSACHUSETTS, ASSIGNOR TO THE HEALD MACHINE COMPANY, OF WORCESTER, MASSACHUSETTS, A CORPORATION OF MASSACHUSETTS

GRINDING MACHINE

Application filed May 9, 1928. Serial No. 276,381.

The present invention relates to grinding machines, particularly of the internal type, and contemplates a machine which is adapted to grind a plurality of workpieces (or one workpiece having a plurality of surfaces to be ground) to predetermined sizes or dimensions, the grinding operation on each workpiece surface being automatically terminated as soon as, but not before, the particular surface being ground has arrived at the finished size.

The main object of the invention is to provide a grinding machine fulfilling the above conditions. Owing to the fact that grinding wheels do not have an absolutely uniform consistency and, no matter how carefully graded, vary among themselves, it is impossible, in the ordinary grinding machine having no automatic means of control, to establish any accurate relationship between two or more grinding wheels and those mechanisms producing the cutting feed for such wheels, that will insure the completion of one surface being operated upon, simultaneously with the completion of grinding on another given surface. With the use of a caliper mechanism and automatic instrumentalities to cause the grinding to cease when one surface has reached a particular size, there would still be no assurance that such termination of the grinding would correspond with any predetermined size of any other surface being operated upon. If two separate caliper mechanisms were employed each surface could be brought to accurate size in accordance with the separate mechanisms, but there would then be no relationship between the rates of grinding that could be relied upon, and the time element would be totally indeterminate. Such a machine would, indeed, consist in little more than two grinding mechanisms mounted upon a single base operating independently and would have all the disadvantages of such an arrangement. By utilizing, however, the grinding system or control which is the subject matter of my own prior invention and which is disclosed in a copending application Serial No. 48,734 filed on August 7, 1925, now Patent No. 1,682,672, granted August 28, 1928, in which

the cutting surface of a grinding wheel, by a dressing operation, is definitely made tangent to a known plane but slightly removed from the finished surface locus of a workpiece, and the grinding wheel is subsequently advanced through a limited distance beyond said plane, I am enabled as hereinafter described to synchronize a plurality of grinding operations so that they will be completed at the same instant.

In carrying out the present invention I cause a plurality of grinding wheels to move in unison in relation to the work surfaces which they are operating upon;—that is to say when one grinding wheel is moving on that stroke of its relative traversing movement that carries it into the workpiece every other grinding wheel is doing the same; and when one grinding wheel is reversed in relation to its workpiece every other grinding wheel is so reversed whether or not the length of the traversing strokes be the same. Furthermore the cutting feet is actuated synchronously in respect to the grinding of the several work surfaces. This, therefore, is another object of the invention and in carrying it out I have shown an illustrative embodiment in which the work is held in a single rotating chuck and a pair of grinding wheels are given traversing motions in relation to this chuck which are opposite in direction.

It is a further object of the invention to provide means for the synchronization of the motion of the grinding tables, and this is accomplished by positive rack and gear connections, whereby the tables must always travel at least at a definite speed relationship and be reversed at the same time.

A further object of the invention is the retention of the advantages of fluid pressure actuation of the tables together with the positive mechanical connections already set forth and to that end the invention provides fluid pressure actuating means for each table with a single control mechanism which is governed by the motion of a single table.

The above and other advantageous features of the invention will more fully appear in the following detailed description, taken

in connection with the accompanying drawings, in which:—

Fig. 1 is a front elevation of a grinding machine embodying the invention.

5 Fig. 2 is a rear elevation of the said machine.

Fig. 3 is a sectional view, on the line 3, 3 of Fig. 1, and showing the work head and lateral feeding mechanism.

10 Fig. 4 is a fragmentary elevational view of the rear of the machine, with certain parts removed, showing the cross slide ways and a certain fluid pressure cylinder in section.

Fig. 5 is an isometric view showing the actuating mechanism for the transverse feed 15 detached from the machine.

Fig. 6 is a detached isometric view showing certain table controlling mechanism.

20 Fig. 7 is a detached isometric view of certain speed control and dresser actuating mechanism.

Fig. 8 is a fragmentary view of the table synchronizing mechanism, the tables or carriages being shown in section.

25 Fig. 9 is a diagrammatic or schematic view of the fluid pressure actuating mechanism for the machine.

Fig. 10 is a wiring diagram.

Like reference characters refer to like parts 30 in the different figures.

Referring particularly to Figs. 1 and 2, the machine provides a pair of reciprocating tables or carriages 1 and 2 of the same general type as the single table or carriage provided 35 in the ordinary internal grinding machine.

Said tables respectively carry wheel heads 3 and 4 of usual construction for the support of grinding wheels 5 and 6 mounted on rotatable spindles 7 and 8, the latter projecting 40 in opposite directions for the operative engagement of said wheels with workpieces mounted in a rotatable chuck 9 that is open at both ends, and mounted in a centrally located workhead 10 between said tables.

45 In the machine herein illustrated the grinding wheels are rotated at high speed in any usual manner, for instance by belt drive, Figs. 1 and 2, from motors 11 and 12 carried by the tables 1 and 2 respectively. The one or more workpieces which may be mounted in the single chuck 9 are rotated at a slower speed, such rotation being imparted from a motor 50 13 mounted on the back of the machine base.

55 As shown in Figs. 2 and 3, a belt 14 passes around the chuck 9 and through slots 15, 16 provided by the work head 10, said belt passing downwardly to a driving pulley 17 located on a horizontal drive shaft 18 that is 60 rotated by the motor 13. A spring actuated belt tensioning device 19 removes whatever slack there may be in the belt and allows of limited motion of the work head 10 transverse to the direction of reciprocation of the 65 tables 1 and 2, said transverse motion to feed

the wheels and workpieces in cutting relation being hereinafter described.

So far as it relates to certain aspects of the present invention, the back and forth movement of the tables 1 and 2 to cause the rotating grinding wheels 5 and 6 to make the required interior traverse of rotating workpieces may be imparted in any well known manner.

70 Preferably, however, fluid pressure controlling and reversing mechanism of the type disclosed in U. S. Letters Patent No. 1,582,468 to Heald and Guild is employed.

According to the present invention, a single controlling and reversing mechanism is utilized, said mechanism being actuated from the movement of one of the tables (as herein 75 shown the table 1) which provides spaced adjustable dogs 20 and 21, adapted to alternately engage and move an interposed member 22,

whose position controls the direction of travel of both tables. Said member is connected, as by connections shown in the afore- 80 said Heald and Guild patent, to a rotatable valve member 23. The valve member 23 may

be of the form shown in the above mentioned 85 patent, or it may be of the simplified construction illustrated in Fig. 9 of the present drawings; at all events when in one extreme position it admits fluid to the outside ends of

a pair of cylinders 25 and 26, which contain 90 pistons, not shown, that are connected by piston rods 27 and 28 with the tables 1 and 2 respectively; while in the other extreme position of said valve member 23 fluid is admitted to the adjacent ends of said cylinders.

95 Referring now to the fluid pressure diagram of Fig. 9, the reversing valve member 23 is located in a suitable casing 29 on the front of the machine, which casing provides

a passage 30 to lead the pressure fluid to said 100 valve, said casing also providing an exhaust passage 31, and passages 32 and 33 to lead the fluid to the different ends of said cylinders 25 and 26.

Fluid is forced by a pump 34 into a supply pipe 35 which connects to the passage 30; the exhaust passage 31 is connected 105 by means of piping 36 to the usual sump or tank located in the machine base, and not herein shown. The passage 30 is provided

with a rotatable plug or throttle valve 37, the angular position of which can be adjusted 110 from the front of the machine by means of a handle 38, in order to set the normal rate of

speed of the tables 1 and 2.

115 The passage 32 connects, by means of piping 39 and 40, to the right-hand end of the cylinder 25, and by means of piping 39 and 41, to the left-hand end of cylinder 26, the pipes 40 and 41 being branches of the pipe 39,

120 as clearly shown in the aforesaid fluid pressure diagram. In similar fashion the passage 33 connects by means of piping 42 and branches 43 and 44 to the left-hand end of

the cylinder 25 and the right-hand end of the cylinder 26. It is obvious, therefore, that 125

130

135

140

145

150

155

160

when the valve 23 is in the position shown in Fig. 9 the pressure fluid will be admitted to the right-hand end of the cylinder 25 and the left-hand end of the cylinder 26, and allowed to exhaust from the opposite ends of said cylinders respectively, and the tables 1 and 2 will move towards each other or inwardly of the machine, while rocking of the valve clockwise to allow fluid to flow outwardly through the passage 33 and to return through the passage 32 will cause the tables to move away from each other or outwardly of the machine.

The above-described fluid pressure means to actuate the tables 1 and 2 in unison insures that they will move oppositely and be reversed at the same time, but, owing to the non-positive nature of the drive, and because there is nothing to compel equal quantities of fluid to enter each cylinder, there is no assurance that the tables will travel at the same speed, and consequently no assurance that they will be reversed when located at the same distance from the center of the work head 10. In fact, as the resistance against one table may be, and often is, different from that against the other table, due to difference in the friction of the several ways or other causes too numerous to mention, the table 2, unless the further mechanism which will now be described were provided, might ultimately undergo its reciprocation in an entirely different position relative to the work head 10 from the table 1, the position of which alone is accurately controlled by the fluid pressure actuating mechanism, by reason of the fact that the controlling dogs 20 and 21 are attached to it. In order, therefore, to retain the advantages of the fluid pressure method of table actuation, and the single control thereof, and yet keep the tables always in the same relative position on the opposite sides of the work head 10, the tables are connected together by mechanical means, which will now be described.

As shown in Fig. 8, each table 1 and 2 provides a rack, 47 and 48 respectively, attached to its under side. Meshing with one of these racks is a spur gear 49, rotatably mounted on a stationary stud 50, while a somewhat smaller spur gear 51, mounted on a stationary stud 52, meshes with the other rack. The gear 49 meshes directly with a long rack 53 that is supported on flanged rollers 54 and 55 which are rotatably mounted on stationary studs 56 and 57. The gear 51 meshes with a gear 58, mounted on a stationary stud 59, and said gear 58 meshes with the long rack 53. It will at once be seen that the tables 1 and 2 are connected positively and must move in opposite directions at equal rates of speed, from the fact that there are two gears 51 and 58 interposed between one table rack and the long rack 53 and only one between the other table rack and

said long rack. It is, of course, entirely immaterial which table rack connects to the long rack through the single gear, and which through the two gears, except that the original positioning of the long rack in relation to the tables is dependent upon this selection.

The aforesaid stationary studs 50, 52, 54, 55 and 59 are conveniently fastened to the inside of the base of the machine, said base comprising front and back walls 60 and 61 with a space between them, as is common in internal grinding machines. The position of the spur gears 49, 51 and 58 and of the rack 53 in relation to the machine as a whole can be clearly seen in dotted lines in Fig. 2.

The work head 10 is carried by a cross slide 10a which is mounted on ways 62 provided by the base of the machine, for the movement of said work head laterally in respect to the grinding wheels 5 and 6. Referring now to Fig. 3, a transverse feeding element for said cross slide, here shown as a screw shaft, is indicated by the numeral 63. Rotation of this shaft in a clockwise direction (in this particular embodiment of the invention) is adapted to draw the work head to cause a workpiece or workpieces therein to move in cutting relation to the grinding wheels 5 and 6. Said screw shaft 63 is adapted to be rotated manually by means of a hand wheel 64 and mechanically from a ratchet wheel 65, the latter being automatically given a step-by-step movement, as will hereinafter appear. Ratchet wheel 65 is directly fastened to an annular piece 64a, which is herein shown as formed integrally with the hand wheel 64. Fastened to the piece 64a is a stud 66, which rotatably carries a pair of gears 67 and 68, formed out of a single piece.

Keyed or otherwise fastened to the shaft 63 is a sleeve 69. This sleeve provides a convenient bearing for the annular piece 64a, and it also provides a gear portion 69a which meshes with the gear 67. Another sleeve 70 surrounds the shaft 63, but is not fastened thereto. This sleeve has a gear portion 70a which meshes with the gear 68.

Assuming for the moment that the sleeve 70 is stationary, it will be apparent that rotation of the elements 64, 64a, and 65 will cause rotation of the screw shaft 63, but at a very much reduced speed, since the gears 67 and 68 differ slightly, and only slightly, in diameter.

Referring now to Figs. 1 and 3, a ring 71 is carried by the element 64a. This ring 71 can be adjustably clamped in any desired angular relation to the element 64a, and on the ring is a cam projection 72. The latter, as shown in the wiring diagram of Fig. 10, is adapted to engage successively with rock levers 73 and 73a, to effect the engagements, respectively, of contact terminals 75, 76 and 75a, 76a. These pairs of terminals prefer-

ably have the construction and mounting shown sectionally in Fig. 3 for the pair 75, 76. As shown in said figure, the rock lever 73 is pivoted at 74, and when the cam member 72, by engagement with said rock lever moves it upwardly, the terminal in question 75, engages the terminal 76. The latter is mounted on the front of a plunger 77 which is slidably held by a cylindrical member 78 of insulating material. Around a reduced portion of the plunger 77 and inside the said cylindrical member 78 is a spring 79, which presses the plunger 77 forwardly, causing the engagement of nuts 80 with the cylindrical member 78, said nuts serving to adjustably fix the initial position of the plunger 77 and also to allow of attachment of electric wires to the plunger. The above construction allows a firm contact to be made, using heavy rock levers for accuracy, yet without danger of breaking any parts.

The step-by-step rotation of the screw shaft 63 to move the cross slide 10a on its ways 62 is induced by the reciprocatory movement of the tables 1 and 2. Referring to Figs. 1 and 5, a plate 81, attached to the front of the machine, provides a boss 82 through which extends a horizontal rod 83 suitably fastened to said boss. The rod 83 is screw threaded and provides a double pair of adjustment nuts 84 and 85 which receive the thrust of a pair of compression springs 86 and 87 respectively mounted on said rod 83. Slidably mounted on said rod 83 between the springs 86 and 87 is a block 88 having a hole therethrough, this block being rigidly attached to and depending from a long bar 89. The right-hand end of the bar 89 is supported by a roller 81a located on the front of the plate 81, and the left-hand end of said bar is pivotally attached at 90 to the depending arm 91 of a three armed lever. This lever is mounted on a stud 92 projecting from the front of the machine frame, and provides, in addition to its depending arm 91, a pair of upwardly extending arms 93 and 94. Arm 93 has attached thereto a hardened block 95 providing an inclined or cam surface, while arm 94 provides a roller 96 which lies in the path of a block 97. The block 97 is adjustably fastened to the table 2 as by means of the usual hand screw nut 98 and screw rack 99 formed on said table.

In the normal reciprocatory movement of the tables 1 and 2 to cause the grinding wheels 5 and 6 to grind one or more work-pieces in the chuck 9, the block 97, at each end of the inward stroke of said tables, engages the roller 96 and rocks the lever 91 in a clockwise direction. This draws the long bar 89 to the left, against the tension of the spring 87, and causes a cam member 100 to engage and lift a roller 101. The roller 101 is carried by a member 102 that is pivotally mounted at 103 on the machine frame, as

shown in dotted lines in Fig. 1. When the roller 101 and consequently also the member 102 is raised as aforesaid, a pawl 104, which is pivotally carried by said member 102, is pressed into engagement with a cam member 105 and is thus forced towards the ratchet wheel 65 and moves it. The pawl 104 is normally kept out of engagement with the ratchet 65 by means of a spring device not shown, and thus the cross feed mechanism can be freely turned in either direction by means of a hand wheel 64 except when the cam member 100 is actually engaging the roller 101. The cam member 105 is adjustable to force the pawl toward the ratchet wheel either at the inception of its stroke or at any predetermined point in said stroke, and by this means the amount of feed can be adjusted.

This automatic step-by-step movement of ratchet 65 in response to the actuation of pawl 104, induced by the reciprocation of the table 2 (which as heretofore clearly described moves in unison and in exact accordance with the table 1 only always in the opposite direction of travel) moves the annular member 64a, and consequently also the ring 71 and the cam projection 72. The front projecting portions of the rock levers 73, which as clearly shown in Fig. 3, desirably have the shape of bell crank levers, lie in the path of this cam projection 72, and consequently movement of the latter causes contact between first one pair of terminals 75, 76 and subsequently between the other pair of terminals. For the relation between the two sets of similar contact mechanisms, described in a single description above, see Fig. 1 and also the wiring diagram of Fig. 10; in the latter figure the terminals 75 and 76 that are first brought together in the operation of the machine are so designated while the exactly similar but subsequently closed contact terminals are designated 75a and 76a. When the terminals 75 and 76 are brought together, an electric circuit is closed which, by the mechanism presently to be described, causes the tables 1 and 2 to simultaneously withdraw the respective grinding wheels 5 and 6 a limited distance from the work, and simultaneously causes a pair of wheel dressing devices or diamonds 107 and 108 to move into the amplified paths of said grinding wheels, thereby to true the periphery of the latter as they pass the points of said diamonds.

As shown by the wiring diagram of Fig. 10, electric current may be supplied by a generator 109 driven continuously by any suitable means, for example by the shaft 18. One terminal of this generator 109 is grounded as shown at 110 and the other is connected by a supply wire 111 to the left-hand bar or plate 112 of a switch,—the latter being designated as a whole by the numeral 113 and being disposed as shown in

Fig. 1 on the front of the machine. Said switch 113 provides another contact plate or bar 114 arranged to the right of the bar 112 and adapted to be alternately connected and disconnected from said bar 112 by a connector 115, which is mounted on an oscillatory member 116. The latter is pivoted at 117 and in its normal position, as shown in Fig. 10, disposes the connector 115 in contact with 10 and across the two plates 112 and 114; in the other position of movable member 116 the plates or bars 112, 114 are entirely disconnected.

When the grinding wheels 5 and 6 are taking the preliminary cuts on a workpiece or workpieces, the oscillatory switch member 116 occupies said normal position of Fig. 10 and under these conditions the supply wire 111 from the generator 109 is connected to a 20 wire 118 running from the plate or bar 114 of the switch 113. Said wire 118 runs to the coil of an electromagnet 119 disposed on the front of the machine, as shown in Fig. 1. A return wire 120 from the coil of this electromagnet 119 connects it to the contact 25 terminal 76. When the terminals 75 and 76 are brought together as above described, by the action of the cam 72, the circuit through electromagnet 119 is completed, since the terminal 75 is grounded as shown at 121, Fig. 10. This energizes the electromagnet 119, causing attraction of an armature member 122, and the consequent elevation of its attached lever arm 123, these parts being pivoted at 124 on the front of the machine. Such movement of the lever arm 123 responsive to the engagement of cam 72 with the first rock lever 73 is made use of to automatically interrupt the grinding operation for 35 the dressing and truing of the wheels 5 and 6. This involves the withdrawal of the grinding wheels 5 and 6 from the wheel head 10, and the disposal, in their temporarily amplified path of movement of the dressing devices or diamonds 107 and 108 respectively; these two operations are effected through the medium of the lever arm 123 in the following manner:—

Referring to Fig. 1, the lever arm 123 has 50 a downward extension 125, which is slidably connected to a valve member 126. The latter is best shown in the fluid pressure diagram of Fig. 9, and as shown in said figure, the valve member is adapted to connect piping 127 shunted into the main pressure piping 35 to diamond operating piping 128. To that end a valve casing 129 in which the valve 126 is located provides three ports 130, 131, and 132 which are, in order, a fluid entrance port 130, a fluid exit port 131 connected to the piping 128, and a discharge port 132. When the valve member is in the position shown in Fig. 9, which it assumes prior to the energization of magnet 119, pressure fluid can not go 65 through the valve;—on the contrary, the pip-

ing 128, which leads to the diamond controlling mechanism, is in direct connection with the discharge port 132, allowing the fluid to be discharged into the main supply tank already mentioned. When however, the valve 70 126 is moved, as above set forth, a reduced portion 133 on said valve 126 allows the pressure fluid to enter the piping 128, and at the same time the solid portion of said valve 126 closes the exhaust port 132.

The piping 128 leads to a port 134 in a hollow cylinder 135 which is located on the back of the machine and supported by the cross slide 10a. The relation of this cylinder to the machine as a whole is best illustrated 80 in Fig. 2, while the fragmentary isometric view of Fig. 7 shows its relation to the rest of the diamond operating mechanisms. Referring for the moment, however, to Fig. 9, the cylinder 135 provides a piston 136 whose rearward movement, in response to the pressure of the fluid admitted to the cylinder 135 lowers both of the diamonds 107, 108 into the path of the grinding wheels 5 and 6.

The diamonds 107 and 108 are embedded in 90 metal plugs or nibs which are held by oscillatory members mounted in antifriction bearings, and delicately adjustable in their operative positions by means of knobs 137 and 138 respectively. The construction and 95 mounting of the oscillatory members which hold the diamonds, the stops which locate them at a definite plane when moved into the paths of the grinding wheels 5 and 6 and all other details of the supports for said diamonds form no part of the present invention, 100 being fully described in U. S. Letters Patent No. 1,655,903 granted on January 10, 1928, to Guild and Grimshaw. It is sufficient to note for the purpose of the present invention that 105 the two mechanisms of the type shown in the aforesaid Guild and Grimshaw patent are provided by the present machine, these being designated generally by the numerals 139 and 140 respectively. These mechanisms are sym- 110 metric, that is to say identical in construction, but having similar parts located on opposite sides. The oscillatory members referred to and fully described in the said patent are connected to links 141 and 142 respectively in the case of the diamonds 107 and 108, and rearward motion of said links causes the diamonds to be moved from the position shown in Figs. 1 and 2 into the path of the 115 grinding wheels 5 and 6.

Referring now to Fig. 7, the piston 136 provides a rearwardly projecting pin 136a which is in engagement with the front face of a short arm 143. Said arm 143 is fastened to a horizontal shaft 144 suitably mounted in bearings 145 and 146 respectively provided by the cross slide 10a or some part connected thereto, and on the ends of said shaft 144 are fastened a bell crank lever 147 and an arm 148. An upwardly extending arm 147a of the 120 125 130 135 140 145 146 147 148 147a

bell crank lever 147 provides a hole there-through through which passes the link 141. Similarly the arm 148 provides a hole through which extends the link 142. Generally U-shaped brackets 149 and 150 are located on the link rods 141 and 142 respectively and constitute stops to transmit the motion of the parts 147a and 148 to said links, compression springs 151 and 152 being placed on the rods between one end of the brackets and the arms in order that the downward movement of the diamonds 107 and 108 may be cushioned. From the foregoing description it will be apparent that rearward movement of the piston 136 results in counterclockwise turning of the shaft 144, Fig. 7, which moves the arms 147a and 148 rearwardly of the machine and thus draws the links 141 and 142 in the same direction to move the diamonds 107 and 108, mounted on oscillatory members, as described in the aforesaid Guild and Grimshaw patent, into the paths of the grinding wheels 5 and 6.

As has been stated, the other operation inaugurated by engagement of terminals 75 and 76 is the automatic amplification of the reciprocatory path of the tables 1 and 2 to carry the wheels 5 and 6 past the dressing devices 107 and 108. As shown in Fig. 6, the left-hand table dog 20, which limits the outgoing movement of the tables 1 and 2, is carried by a block 153 which, instead of being secured directly to the table 1, as is the case with the block 154 of dog 21, is mounted so as to be capable of sliding freely longitudinally of said table. Under normal conditions, when the tables are making their usual working reciprocation to traverse the grinding wheels 5 and 6 back and forth within the workpiece or workpieces, the block 153 of dog 20 is held in definite spaced relation to block 155 which latter, the same as the block 154 of right-hand dog 21, is a stationary block adapted to maintain its predetermined setting or adjustment longitudinally of the table 1, as given it by any suitable adjustment or holding device, as such the hand screw nuts 156, 156, applied to both blocks 154 and 155 and engaging with a screw rack 157 provided by the table 1.

The device employed to hold the slideable block 153 in spaced relation to the fixed block 155 is here shown as a latch lever 158, pivoted at 159 on block 155, and having its free end disposed by gravity in abutting relation to a shoulder 160 on block 153, thereby holding the block 153 at a predetermined distance to the right of block 155. When the latch member 158 is lifted to free its end from the shoulder 160, the normal connection between the slideable block 153 and the fixed block 155 is broken, and when this occurs on the movement of the tables outwardly, the dog 20 will bear without effect against the member 22. Thus the outward movement of the tables 1 and 2 in this particular stroke will be ex-

tended beyond the usual reciprocatory working path, and the grinding wheels 5 and 6 will be carried past the dressing devices 107 and 108 which, as already described have been moved into operative position.

This amplified travel of the tables 1 and 2 involves relative sliding movement between the table 1 and the block 153, owing to the obstruction which the reversing member 22 imposes against the dog 20 to prevent the block 153 from moving with the table; finally the block 153 brings up against the block 155, whereupon the solid backing thus afforded for the block 153 enables the dog 20 to shift the member 22. This procures reversal of the tables 1 and 2, and the left-hand movement of the table 1 thus inaugurated is caused to restore the parts automatically to normal position in the following manner:—

As best shown in Fig. 1, a member 161 pivotally mounted on the frame of the machine and pressed upwardly by a spring 162, provides beveled or inclined surfaces at each side thereof which lie in the path of similarly beveled or inclined surfaces provided on the underside of the slideable block 153. In the normal grinding operation of the machine the inclined surfaces on the member 161 offer no effective obstruction to the back and forth travel of the block 153, since contact between them serves merely to compress the spring 162. When, however, the block 153 has been freed as above described, the ensuing reversal of the table finds the right-hand beveled or inclined surface of member 161 in position to contact with the left-hand bevel corner of said block, and the obstruction afforded is sufficient to overcome whatever friction there may be tending to cause the block 153 to move to the left with the table. The block 153 being thus held stationary while the table 1 and the block 155 continue to move to the left, the latch member 158 finally resumes its normal position relative to the block 153, the end of said latch member dropping behind the shoulder 160, and the parts are thus automatically restored to normal position at the conclusion of each single amplified reciprocation of the tables 1 and 2.

Said single amplified reciprocation of the tables 1 and 2 for wheel dressing purposes is inaugurated automatically when the contacts 75 and 76 are brought together, as already described, the lever arm 123 being raised at that moment in consequence of the energization of electromagnet 119. The said lever arm 123 lies, as shown in Fig. 6, in the same vertical plane as the latch lever 158, and since the contacts 75, 76 always come together at a definite predetermined position of the tables 1 and 2, owing to the fact that the ratchet wheel 65 is actuated from the movement of said tables by cam means described, the parts are so proportioned that the right-

hand end of the latch lever 158 is located at that time above the right-hand end of the lever arm 123 and raising of the latter causes said lever arm to be lifted with the result 5 already set forth.

On this amplified dressing stroke of the tables, an arm 163, Figs. 1 and 6, pivoted at 159 and hanging by gravity as shown, strikes an arm 164 of movable switch member 116 10 thereby rocking the connector 115 of said switch member away from bar 114 (see Fig. 10), which prevents a repetition of the dressing stroke.

To prevent further dressing of the grinding wheels 5 and 6 by the dressing devices 107 15 and 108, when the tables 1 and 2, as will presently be described, are moved outwardly for the final separation between grinding wheels and workpieces which occurs upon completion 20 of the grinding operation, the cylinder 135 must be relieved of fluid pressure, and said dressing devices moved into their inoperative positions as shown in Figs. 1 and 2. To that end automatic means is provided for 25 returning the valve member 126 to its former position as shown in the fluid pressure diagram of Fig. 9, in which position the pressure fluid is cut off from said cylinder 135 and said cylinder is directly connected with 30 the pressure fluid supply tank or pump through the exhaust port 132. To that end the lever arm 123 provides a vertical surface 165 which, upon reversal of the tables 1 and 2 at the end of the aforesaid amplified dressing 35 stroke, is engaged by a vertical surface 166 provided by a portion of the block 153. Engagement of said surfaces, since the block 153 is then moving to the right, moves the lever arm 123 in a clockwise direction, and consequently shifts the valve member 126 to the left as will be seen from a consideration 40 of Fig. 1.

The foregoing means relieves the diamond 45 operating cylinder 135 and the piston 136 therein of any pressure, but it does not move the diamonds 107 and 108 to their inoperative position. Mechanical means positive in its 50 nature is provided to accomplish this, and it comes into operation substantially as the grinding wheels 5 and 6 re-enter the work-piece held in the chuck 9. As shown in Figs. 2 and 7, the table 1 carries on the rear thereof a cam bar 167, which has a horizontal surface 168 and an inclined surface 169 on its lower side. A roller 170 on the end of an arm 171 that is fastened to a shaft 172 lies in the path of these surfaces. The shaft 172, as shown in Fig. 2, is supported in bearings 173 and 174 provided by the machine frame, and adjacent the bearing 174, a short arm 175 is fastened to said shaft 172. The arm 175 extends substantially horizontally and rearwardly from the shaft 172 and is connected by means of a link 176 to the rearwardly 55 extending arm of the bell crank lever 147. It

will at once be apparent that when the inclined surface 169 of the cam member 167 engages the roller 170, the shaft 172 will be rocked in such a direction that the link 176 will be moved upwardly, and this motion, transmitted through the bell crank lever 147 to the shaft 144, moves both of the links 141 and 142 forwardly, and thus positively raises both of the diamonds 178 as will be seen from an inspection of the aforesaid patent to Guild & Grimshaw. Engagement of the inclined surface 169 with the roller 170 occurs when the tables 1 and 2 have almost carried the grinding wheels 5 and 6 back into the work-pieces being ground, and in the subsequent 70 operation of the machine, during the reciprocatory travel of said tables to grind the work-pieces to the ultimate required dimensions, the horizontal cam surface 168 is located 75 above the roller 170 and thus positively prevents movement of the diamonds 107 and 108. The horizontal surface 168 also prevents premature movement of the diamonds 107 and 108 on the dressing stroke, that is to say before the spindle sleeves 7a and 8a have moved 80 beyond the diamonds 107 and 108.

In order to cause the tables 1 and 2 to travel at reduced speed during the dressing operation thus to prevent the formation of grooves in the grinding wheels 5 and 6, and in order 85 also, when desired, to cause the said wheels to take the finishing cuts on the workpiece or workpieces at a reduced traversing speed, there is provided a valve 177;—see especially 90 Figs. 2, 7 and 9. The construction of this valve is not illustrated herein since it may be of any desired type; it is sufficient to note that turning of a valve shaft 178 will result 95 in restricting the flow of fluid pressure through the valve which, as will be seen from 100 an inspection of Fig. 9, is located in the supply pipe 35 that carries the fluid pressure 105 to the reversing valve 23.

Referring again to Figs. 2 and 7, the valve shaft 178 has suitably fastened thereto a short 110 arm 179. To the end of this arm 179 is pivotally attached an upwardly extending link 180 the upper end of which is pivotally fastened to a substantially horizontal arm 181. The other end of said arm 181 provides a 115 hub portion 182 mounted on a stud 183 projecting from the machine frame. The link 180 provides an outwardly extending boss 184 having a vertical hole therethrough, and a rod 185 which depends from and is pivotally attached at 186 to the arm 171 passes through 120 said hole. The rod 185 is screw threaded, and two pairs of adjustable nuts 187 and 188 are located thereon, the former pair being placed above the boss 184, and the latter below it. Assuming 125 the valve 177 to be wide open which is its position when the link 180 is depressed, admittance of fluid under pressure to the cylinder 135 with consequent rocking of the shaft 144, results in rocking of the shaft 172 130

also, through the medium of the link 176, and causes the arm 171 to be lifted, thus raising the rod 185, which will move the link 180 upwardly to turn the shaft 178 more or less 5 depending upon the setting of the nuts 188. Such turning of the shaft 178 restricts the flow of fluid through the valve 177 in accordance with the amount of turning of said shaft, and thus causes the grinding wheels 10 5 and 6 to move slowly past the dressing diamonds 107 and 108. When, upon reversals of the said tables at the end of their outward amplified strokes, the said tables travel inwardly again, the cam bar 167 depresses the 15 roller 170, as already described, and this action moves the rod 185 downwardly, repositioning the link 180 and consequently the shaft 178 more or less in accordance with the setting of the nuts 187. When, upon the 20 completion of the grinding operation upon the particular workpiece or workpieces being operated upon, the tables 1 and 2 move outwardly for final separation between said wheels and the workpieces, a roller 189, attached to the rear of the table 1 and lying in the path of a cam surface 190 provided on the upper part of the arm 181, strikes said cam surface and moves the arm 181 and consequently the link 180 downwardly to open 25 30 the valve 177 to allow the maximum flow of pressure fluid therethrough, provided the nuts 187 were set so that the valve was not fully open subsequent to the dressing operation. If the valve had been reset completely, as it would be if the nuts 187 were screwed 35 downwardly to remove all play between the boss 184 and the nuts 187 and 188, the roller 189 will merely pass over the cam surface 190 without effect, but at all events, the 40 machine provides automatic means for insuring that the valve 177 will be fully open at the end of each grinding operation.

After the wheel dressing operation above described, and with the resumption of grinding, the further feeding of the work head 10 45 in relation to the grinding wheels 5 and 6 involves further clockwise rotation of the ring 71, which ultimately carries the cam 72 into engagement with the second rock lever, 50 which is designated 73a on the wiring diagram of Fig. 10 to distinguish it from the first rock lever designated 73 on said diagram. The parts are so set that this engagement and the consequent rocking of this lever 55 73a that carries the contact 75a, brings together the terminals 75a and 76a just as the workpiece or workpieces reach the exact desired size. This engagement of these terminals completes an electric circuit through 60 a second electromagnet which is designated by the numeral 191 on Fig. 10 and which is located on the front of the machine, directly 65 behind the electromagnet 119. The electric current proceeds from the generator 109 by 70 75 way of a branch 111a of the conductor 111

to said electromagnet 191, thence by a conductor 192 to the contact terminal 76a, thence through the terminal 75a into the lever 73a, which is grounded by reason of being uninsulated from the machine as diagrammatically illustrated at 121 in said Fig. 10; and since, as aforesaid, the other terminal of the generator 109 is also grounded the circuit is complete. Energization of this electromagnet 191 causes attraction of an armature member 193 which, together with an inclined lever arm 194 and a depending arm 195, all conveniently formed in one piece, is pivotally mounted on the same spindle 124 which forms the pivot for the armature member 122 and its similar associated parts. 75 80

The depending arm 195 is connected to a 85 slidable valve 196 located in a valve casing 197, said valve and said casing being located directly behind the valve member 126 and the casing 129 respectively. Refer to Fig. 1 for the position of these parts and to Figs. 9 and 10 for the construction. As is the case with the casing 129, the valve casing 197 provides three ports 198, 199, and 200, which are respectively a fluid entrance port, a fluid exit port, and a discharge port. When the valve member 196 is moved to the right by energization of the electromagnet 191, this 90 95 slidable valve mechanism, which may be identical in construction with the slidable valve mechanism directly in front of it, which has already been described, admits fluid under pressure from branch piping 127a, connected with pump 34, to piping 201 leading to a cylinder 202 located on the back of the machine base. In this cylinder 202 there is a piston 203 which may be seen in the fluid pressure diagram of Fig. 9 and the fragmentary view of Fig. 4, and movement of this piston in response to fluid pressure actuation causes the grinding wheels and the workpieces to be immediately separated in a direction laterally of the machine in the following manner. 100 105 110

As shown in Fig. 3, the screw shaft 63 is provided with a shoulder 204 and spaced from this shoulder 204 is the right-hand threaded end of the shaft, which is adapted 115 to receive a nut 205. Between the shoulder 204 and said threaded end, the shaft 63 is a plain cylinder, and on this cylindrical portion are the inner races of a pair of ball bearings 206 and 207. The inner race of bearing 120 206 bears against the shoulder 204, while the inner race of bearing 207 is engaged by the nut 205. The outer race of bearing 206 engages a shoulder 208, while the outer race of bearing 207 engages a shoulder 208a, both 125 of said shoulders being provided on the internal cylindrical surface of a member 209.

The member 209 is externally threaded and is received in a threaded portion of a member 210 which, as shown in Fig. 4, is fastened 130

to the machine frame below the ways 62. It will be seen that so long as the member 209 remains unmoved, the shaft 63 will be held from axial movement, and consequently the position of the cross slide 10a upon the ways 62 will depend upon the rotation of said screw shaft responsive to the automatic feed as already described, but that turning of the member 209 will shift the whole screw shaft 63 and for that matter also the hand-wheel 64 and associated parts on the front of the machine in a lateral direction. The member 209 is adapted to be turned upon movement of the piston 203, and to that end an arm 211 which provides a collar portion 212 suitably fastened to the member 209 is engaged by the end of the piston 203 as clearly shown in Fig. 4. Admission of fluid pressure to the cylinder 202, therefore, which occurs almost instantaneously with the energization of the electromagnet 191 causes the member 209 to be turned, thus moving the screw shaft 63 rectilinearly, and the direction of the threads on the member 209 and 210 are such that this shifting of the screw shaft 63 moves the work head 10 towards the back of the machine, thus moving the ground workpieces laterally with respect to the grinding wheels 5 and 6 and definitely terminating the grinding operation. This lateral separation of the grinding wheels and workpiece or workpieces prevents scratching or marring of the highly polished finished surfaces as the grinding wheels emerge therefrom.

Energization of the electromagnet 191 effects such emergence, causing the tables 1 and 2 to travel outwardly of the machine away from each other and thus carrying the grinding wheels 5 and 6 away from the work head 10, so that the operator can remove the finished workpiece or workpieces from the chuck 9. To that end the left-hand table dog 20 is pivotally attached to its carrying block 153 and normally rests by gravity in the position shown in Figs. 1 and 6, thereby maintaining its free end in position to engage and move the reversing member 22 at the end of the outgoing normally working stroke of tables 1 and 2. When the magnet 191 is energized the lever arm 194 is raised into the path of dog 20 and the latter, on the aforesaid outward movement of the tables, by reason of its pivotal mounting, is free to ride on the upper surface of said lever arm; thus the striking end of said dog 20 is carried clear of the reversing member 22 and the tables continue their outward movement, carrying the grinding wheels 5 and 6 away from the work head 10 and past the then inoperative dressing devices 107 and 108.

Such final motion of separation between the grinding wheels 5 and 6 and the work head 10 at the finish of a given grinding operation returns the speed control valve 177 to

its normal wide open position by the action of roller 189 on the cam surface 190, as has been described. The motion of separation likewise resets the externally threaded member 209 to its initial position, thus shifting the screw shaft 63, so that in a subsequent grinding operation the dressing operation and the cessation of grinding will be brought about at the proper stages in said grinding operation, as determined by the position of the cross feeding elements modified by the action of the cross feed compensating mechanism. The latter mechanism is also operated by the final movement of separation and compensates the feeding mechanism for wear of the grinding wheels and for the material taken therefrom by the dressing operations. Finally the tables are brought to a stop in the retracted position by any suitable mechanism, such as that disclosed in the aforesaid patent to Heald and Guild No. 1,582,468 and thus the given grinding operation is completed and the operator may stop the rotation of the chuck 9, remove the finished work and insert a new piece or pieces.

Such automatic stopping mechanism may take the form of a poppet valve 214 whose head is located in a chamber 215 of the passage 32 and which is normally kept open by a cam member 216 carried by the table 1 and engaging a lever arm 217 which holds said valve 214 open against the tension of a spring 218. When the tables are running outwardly the pressure fluid is returning through the passage 32 past the poppet valve 214, and when the tables reach a certain position the cam member 216 releases the lever arm 217, thus allowing the poppet valve 214 to close under the simultaneous action of the spring 218 and the flow of fluid and this, of course, as it locks the fluid in the cylinders 25 and 26, stops the movement of the tables. It will be apparent that the closure of this valve 214 is no obstacle to restarting of the tables in the opposite direction, as the force of the fluid flowing outwardly through the passage 32 will open it.

The work head 10 is reset automatically to the position it occupied at the completion of the grinding operation just as soon as the grinding wheels 5 and 6 have fairly emerged from the workpieces, and this takes place through positive returning of the lever arm 194 and consequently also of the valve 196 to their original positions, thus cutting off the fluid pressure from the cylinder 202, and opening said cylinder to the exhaust through the port 200. This repositioning of the lever arm 194 is brought about by contact with said arm of the lower corner 219 of the table block 155 as the table 1 travels to the right. There being then no pressure against the piston 203, the latter is returned to its initial position inside the cylinder 202, as shown in Fig. 4, by means of a strong spring 220 acting on the

depending arm 211, and this, of course, turns the member 209 in a counterclockwise direction, Fig. 4, and moves the screw shaft 63 laterally into its normal position.

3 Referring now to Figs. 1 and 5, the table 2 has attached thereto a pivot stud 221 which carries a short arm 222 hanging downwardly therefrom by gravity. The arm is free to turn clockwise to a horizontal position, there being nothing to stop it from moving in this direction, but it can not be moved counterclockwise beyond the vertical position in which it is shown in the drawings, because a shoulder 223 provided by the table or a member 224 fastened to the table and into which the stud 221 is conveniently screwed, backs up said arm 222 and causes it to be rigid and unyielding when forces are applied to move it counterclockwise. In the final movement 20 of separation of the tables 1 and 2 as already described, the arm 222 strikes the inclined surface of the hardened plate 95 on the arm 93 of the three arm member, and thus depresses the arm 93, swinging the member as a 25 whole in a counterclockwise direction, and this action moves the long bar 89 to the right. At the right-hand end of the long bar 89 is a block 225 which normally is barely in contact with a roller 226 provided by a bell crank 25 lever 227 pivoted at 228 on the front of the machine. Movement of the long bar 89 to the right consequently turns the bell crank lever 227 in a clockwise direction and draws a link 229 attached to one end of said bell crank 30 lever downwardly. The link 229 is connected at its other end to an arm 230 which is fastened to a shaft 231, and the consequent downward movement of the link 229 procures limited clockwise rotation of the shaft 231. 35 40 Suitably fastened to the front end of the shaft 231 is a member 232. Said member, of course, receives the clockwise rotation referred to, a spring 233 together with the spring 86 returning the parts to normal position immediately after the operative engagement of the arm 222 and the plate 95. The member 232 pivotally carries at 234 a pawl 235. The latter contains a spring pressed plunger device urging it upwardly, but a pin 50 55 60 65 70 75 80 85 90 95 100 105 110 115 120 125 130 135 140 145 150 155 160 165 170 175 180 185 190 195 200 205 163, being also located in a different vertical plane, strikes an arm 256 of the oscillatory member 116 of the controlling switch 113 and thus connects the contact plate or bar 112 to the plate or bar 114.

Both grinding wheels 5 and 6 now commence their equal and opposite reciprocation in relation to the workpiece or workpieces contained in the chuck 9, the cross feeding mechanism being actuated at the end of each inward stroke of said grinding wheels. There is no assurance that the actual contact between the wheel 5 and the surface it is to grind will occur simultaneously with contact between the wheel 6 and the surface that this wheel is to grind; on the contrary if the amount of stock to be reduced from the different surfaces is different, the initial contact will take place at different times. In practice, the operator may and usually will turn the hand wheel 64 until contact is made on one side or the other, thus speeding the operation of the machine. When, however, actual grinding is taking place at both sides of the work head, both surfaces that are being ground bear the same relationship to their ultimate finished diameters. The machine of the present invention thus makes use of the principle that if a plurality of variables, while approaching their respective limits are always equal, their limits will be equal.

The foregoing relationship between the wheels and workpieces is exactly true only on the assumption that the grinding wheels wear at the same rate. This assumption, however, as hereinbefore pointed out, cannot be relied upon, and therefore the machine provides the automatic dressing instrumentalities hereinbefore described to overcome non-uniformity in wheel wear, and to re-synchronize the relationship between the grinding wheels as close to the time when the grinding operation will cease as is possible. The grinding, therefore, proceeds until such time as the first electric circuit is closed by the coming together of the contacts 75 and 76, whereupon both tables withdraw outwardly and the grinding wheels are dressed and trued as already described. In this outward movement of the tables, the depending arm 163 strikes the arm 164 of the switch member 116 and thus makes the machine ready for the final withdrawal stroke of the tables, but it should be noticed that the movement of the table 1 is not sufficient in this dressing stroke to carry the arm 255 past the switch arm 256.

The grinding is now resumed and the cutting surface of one wheel is exactly the same distance from the desired size of the work surface that it is grinding as the cutting surface of the other wheel is to the finished size of the work surface that it is operating upon. Owing to the smallness of the crossfeed move-

ment required of the workhead 10 between the dressing operation and the completion of the grinding, this equality of the variable remains substantially undestroyed, and both surfaces are completed at the same moment as signified by the bringing together of the contacts 75a and 76a, which immediately causes both tables to withdraw to the inoperative position shown in Figs. 1 and 2.

The machine is not limited to the grinding of holes of the same size, for a small grinding wheel 5 might be employed on one side of the machine and a large grinding wheel 6 on the other side to grind a larger diameter hole, and the difference in the amount, by weight, of the material removed would be compensated for by the greater peripheral speed of the larger wheel, and the machine will thus effectively operate with the same rate of lateral feed for different sized workpieces. Obviously the grinding wheels 5 and 6 do not have to be in axial alinement on their respective tables 1 and 2, and the invention contemplates the adjustability of the work heads 3 and 4 transverse to the line of reciprocation of said tables, but the setting of the machine is somewhat facilitated by having the grinding wheels located in alinement.

The invention possesses great utility in grinding cluster gear pieces, or in the grinding of pulleys or clutches or similar articles that have several surfaces to be ground of equal or different diameters. The machine as shown can even grind as many as four distinct surfaces not located in any given geometrical cylinder, merely by providing two grinding wheels of different diameters on each spindle 7 and 8 and duplicating the dressing points 107 and 108 on each side of the machine. For these and many other purposes for which the machine can be used, it presents very great commercial utility and advantage, as the automatic grinding of a plurality of surfaces by the same operation and setting of the machine accomplishes a tremendous saving.

I claim,

1. In the art of grinding, the improvement which consists in causing a plurality of grinding elements initially bearing a variable relation to a plurality of surfaces to be ground, to bear always equal relationships to said surfaces, by relative advance of said surfaces in respect to said elements, and periodic dressing of said elements to known positions and thereafter to synchronously advance to known limits, thus to cause their limits, which measure the finished size of the several work surfaces, to be equal.

2. In a grinding machine, the combination with a pair of grinding wheels and means to rotate them, of a pair of tables or carriages upon which said grinding wheels are mounted, means to reciprocate said carriages, and separate means to synchronize their recipro-

cations that their simultaneous strokes occur always in opposite directions.

3. In a grinding machine, the combination with a pair of tables or carriages adapted to produce relative traversing movements between grinding wheels and workpieces, of fluid pressure operated means to actuate said carriages independently, and mechanical means connecting said tables to cause them to move synchronously and always in opposite directions.

4. In a grinding machine, the combination with a pair of tables or carriages adapted to produce relative traversing movements between grinding wheels and workpieces, of fluid pressure means to actuate said tables independently, valve means having connections for controlling the admission of fluid to said fluid pressure means so arranged that the tables will always move in opposite directions, and means to operate said valve means from a given table.

5. In a grinding machine, the combination with a pair of tables or carriages adapted to produce relative traversing movements between grinding wheels and workpieces, of fluid pressure means for reciprocating said tables independently, connections for admitting pressure fluid to and discharging it from said means, to operate said tables, a single valve means controlling flow of fluid through said connections, and a single operating means actuated by one of said tables to shift said valve means, whereby said tables will operate synchronously.

6. In a grinding machine, the combination with a pair of tables or carriages adapted to produce relative traversing movements between grinding wheels and workpieces, of fluid pressure operated means operating said tables, connections for admitting and discharging fluid from the operating means to operate said tables, a single valve means controlling flow of fluid through said connections, a single operating means actuated by one of said tables to shift said valve means, and mechanical means connecting said tables to force them to move in unison despite variations in the amount of pressure exerted upon each or the amount of resistance said tables encounter.

7. A grinding machine having in combination, a rotary work holder, a pair of grinding elements, means to reciprocate said grinding elements in unison to cause them to operate on work in said work holder, and means automatically operable at a predetermined time before the completion of the grinding operation or operations to prolong one stroke of each of said elements in different directions to effect a temporary separation between said work holder and said elements.

8. In a grinding machine, a pair of grinding wheels, means for effecting a working traverse between each wheel and the work by

means of separate tables or carriages, means operable automatically before the completion of the grinding operation to amplify the movement of each of said tables, a pair of dressing devices applicable to dress the said wheels at this stage, and means for causing both of said tables to automatically resume their working traverse after said dressings for the final and finishing cuts of the grinding wheels to bring said work to size.

9. In a grinding machine, a pair of grinding wheels having separate and oppositely moving traverses in relation to the work, means for automatically amplifying said traverses in opposite directions when the work, by grinding, has reached a predetermined size, means for automatically disposing a wheel dressing device in the path of each wheel on said amplified traverse thereof, and means for automatically resuming the normal reciprocatory working traverses between grinding wheels and work to bring the latter to the desired finished size.

10. In a grinding machine, a pair of grinding wheels, means for effecting a working traverse between each wheel and the work by means of separate tables or carriages, means operable automatically before the completion of the grinding operation to amplify the movement of each of said tables, a pair of dressing devices applicable to dress the said wheels at this stage, and means for causing both of said tables to automatically resume their working traverses after said dressings for the final and finishing cuts of the grinding wheels to bring said work to size and means to compensate for attrition of the wheels due to wear and dressing.

11. In a grinding machine, a pair of grinding wheels having separate and oppositely moving traverses in relation to the work, means for automatically amplifying said traverses in opposite directions when the work, by grinding, has reached a predetermined size, means for automatically disposing a wheel dressing device in the path of each wheel on said amplified traverse thereof, means for automatically resuming the normal reciprocatory working traverses between grinding wheels and work to bring the latter to the desired finished size, and means operable by one of said tables for effecting relative compensation between said wheels and the work, for the attrition of said wheels, due to wear and dressing.

12. In a grinding machine, the combination with a pair of tables or carriages adapted to produce relative traversing movements between grinding wheels and workpieces, of fluid pressure operated means to actuate said carriages independently, of means to cause the carriages to make an extended stroke upon the completion of the workpieces, and mechanical means connecting said tables to cause them to move syn-

chronously and always in opposite directions.

13. In a grinding machine, a plurality of grinding wheels, workholding means for a plurality of workpieces, means to effect reciprocatory axial traverses of said grinding wheels, relatively to said workholding means, means for effecting a relative cross feed between said workholding means and said 10 grinding wheels, wheel dressing devices, means for causing said grinding wheels to be dressed by said dressing devices, and means for synchronizing the relative cross feed of the several grinding wheels including 15 the aforesaid means for dressing them so that they will bear a variable relation to a plurality of finished surface loci as the cross feed operates, but an always equal relation thereto, the limit of advance measuring the 20 finished loci of the workpieces.

14. In a grinding machine, a rotatable workholding means for a plurality of workpieces, a pair of grinding elements, one on either side of said workholding means, means 25 to reciprocate said grinding elements relative to said workholding means, whereby each grinding element will traverse a workpiece, means to synchronize the traversing motions of said elements, means to impart 30 a relative cross feed between said elements and said workholding means to cause the said elements to cut deeper and deeper into the respective workpieces, a pair of dressing devices, means governed by the progress of the 35 grinding operation to cause the said grinding elements to withdraw from the workpieces and be dressed simultaneously by said dressing devices, means to return said elements to the workpieces, for further grinding after 40 said dressings, and means governed by the further progress of the grinding operation to cause a combined relative lateral and longitudinal separation of the grinding elements and the workholding means, to permit removal of said ground workpieces from the 45 said workholding means.

WALDO J. GUILD.
